UNITED STATES PATENT OFFICE.

JOSEPH E. CRISP, OF SOMERVILLE, AND GEORGE W. COPELAND, OF MALDEN, MASSACHUSETTS, ASSIGNORS, BY MESNE ASSIGNMENTS, TO THE GOOD-YEAR SHOE MACHINERY COMPANY, OF PORTLAND, MAINE.

HAND PEGGING-MACHINE.

SPECIFICATION forming part of Letters Patent No. 569,617, dated October 20, 1896.

Application filed May 23, 1892. Serial No. 433,943. (No model.)

To all whom it may concern:

Be it known that we, JOSEPH E. CRISP, of Somerville, and GEORGE W. COPELAND, of Malden, in the county of Middlesex and State 5 of Massachusetts, have invented certain new and useful Improvements in Hand Pegging-Machines; and we do hereby declare the following, with the annexed drawings, to be a full, clear, and exact description of the invention, such as will enable others skilled in the art to which it appertains to make and use the same.

Our invention relates to improvements upon that class of pegging-machines which 15 are held in one hand of the operator and moved from place to place as the pegs are required, where the plunger of the machine is struck one blow with a maul or other proper hammer held in the other hand of the operator, 20 and the awl is driven and withdrawn, and the peg-cutting, peg-feeding, and peg-driving mechanisms are correctly operated by said blow to supply and drive a peg into the hole made by the awl.

25 These improvements consist in using a shearing-cutter, which cuts the peg-wood and then moves and holds the peg just cut in the path of the driver; also in connecting together the principal parts of the machine, so that the 30 constant concussion of the driver will not cause them to become loose or displaced, while at the same time they can be quickly removed when required; also in various details of the operating parts, which will be hereinafter described.

In the accompanying drawings, Figure 1 is 35 a front elevation of the machine complete. Fig. 2 is a side elevation of the same, viewed from the left of Fig. 1. Fig. 3 is a side elevation of the lower part, viewed from the right of Fig. 1. Fig. 4 is an elevation of the machine, the front plate being removed to show the interior parts, the parts being in the position that they occupy when the awl, 40 driver, peg-cutter, &c., are all up and ready for a blow; Fig. 5, same as Fig. 4, with the awl driven, the peg cut off and moved under the driver ready for the continuation of the stroke to withdraw the awl and drive the peg; 45 Fig. 6, same as in Fig. 4, except that the parts

occupy the position that they are in when a peg has been driven and the awl and peg-cutter have returned to their normal position of rest. Fig. 7 is an elevation showing the mechanism for withdrawing the awl. Fig. 8 55 is a cross-section taken on line $z z$ of Fig. 5. Fig. 9 is a cross-section taken on line $t t$ of Fig. 5. Fig. 10 is a view from the front (inclined) showing the parts more immediately connected with the feeding device. Fig. 11 60 is a vertical section taken on line $x x$ of Fig. 10. Fig. 12 is a view, partly in vertical section and partly in elevation, showing details of the feeding device. Fig. 13 is a view of details relating to the feeding device. Figs. 65 14 and 15 are sectional views in elevation to illustrate the working of the machine. Fig. 16 is a sectional view of part of the throat, showing the relations of peg-wood-guideway, shear, and the driveway for the pegs. Fig. 70 17 is a cross-section showing the bolt A^5 and the shear pivoted thereto.

The outside of the casing is of suitable shape to be grasped in the operator's hand and carries and guides within itself the driver-plunger B, the awl-carrier C, and their operating mechanism. 75

The main part of the casing A, Figs. 1 and 2, has formed on its sides the dovetails A' , and over these dovetails is slid the part A^2 , 80 which thus ties the two sides of the part A firmly together, as shown by Figs. 8 and 9. This part A^2 is held in position by the bolt A^3 , which passes from side to side of the machine for that purpose. 85

At the lower part of the casing A there is formed a dovetail groove A^4 , into which is slid the part of the machine carrying the peg-wood-feeding, peg cutting and delivering mechanism, which is there held firmly in position by the bolt A^5 and its check-nuts A^6 , as shown by Figs. 2, 3, and 17. 90

The driver-plunger B is rectangular in form, and in its interior is the hole B' , which reaches nearly to its lower end. This hole serves to 95 reduce the weight of the plunger and at the same time forms a pocket which carries and guides the raising-spring B^2 . Central with the hole B' through two of the sides of the plunger B are the slots B^3 , wide enough to allow 100

the bolt A³ to pass freely through and long enough to allow the desired reciprocation of the plunger B. Within the hole B' is the raising-spring B², with its lower end resting upon the bolt A³, and when the top of the plunger is closed by the cap B⁴ the spring acts against the inside of the cap and raises the plunger.

From the foregoing it will be seen that to remove the awl or driver from the machine it is only required to take off the cap B⁴ and withdraw the bolts A³ and A⁵, when all parts of the machine can be quickly reached.

To the lower solid end of the driver-plunger B are secured the peg-driver B⁵, a wedge or cam B⁶ for operating the feeding device, and the pin B⁷ for operating the swinging lever D.

The awl-carrier C is also rectangular in form and when in the machine one of its sides contacts with and slides against one of the sides of the driver-plunger B, as shown by Figs. 4, 5, 8, and 9, the awl C and peg-driver B⁵ being secured to these contacting sides, so that they will also contact and slide upon each other, as shown by Figs. 14 and 15. This awl-carrier is operated by the driver-plunger so that it will make one full reciprocation and drive and withdraw the awl when said driver-plunger is descending by the following attachments and connections:

Pivoted to the upper end of the awl-carrier C at C² is the pawl C³, having the downward extension C⁴, against which the spring C⁵ operates to press the end of the pawl toward the driver-plunger, as shown by Figs. 4 and 8. A tooth or notch is formed on the driver-plunger at B⁸, so that it will engage with the end of the pawl C³ when said plunger is raised to its highest position, and as the plunger descends it moves the awl-carrier down and drives the awl into the stock.

There is formed upon or attached to the part A of the casing the stationary cam A⁷, which engages with the downward extension C⁴ of the pawl C³ and which completely disconnects the upper end of the pawl C³ from the tooth B⁸ when the awl-carrier has been moved down the proper distance and leaves the various parts in the position, shown by Fig. 5, from which point the continued descent of the driver-plunger withdraws the awl from the stock by the following mechanism:

In a suitable recess formed in the main part of the casing A back of the plunger and awl-carrier there is hung upon a part of the bolt A³ the compound swinging lever D, as shown in Figs. 4, 5, 6, 7, 8, and 9. This lever is so shaped that as the driver-plunger moves down from the position shown by Fig. 4 to that shown by Fig. 5 the pin B⁷, fixed in and moving with said plunger, will not change the position of the lever. As the descent of the driver-plunger continues below the position of Fig. 5 the pin B⁷ engages with the working face of the lever D and swings it to the left. When the driver-plunger has nearly reached its lowest position, the lever D has

been swung to its extreme limit of motion. This motion of the lever D is transmitted to its upper extension D', which engages with the roll C⁶, which is connected to the awl-carrier by the pin C⁷, and raises the awl-carrier and withdraws the awl from the stock. There is also a downward extension D² from the lever D, which as the driver-plunger is ascending engages with the pin B⁷ and swings and holds the lever D to its extreme limit of motion to the right ready for another descent of the driver-plunger. To give the pin C⁷, fixed in the awl-carrier C, suitable stability to resist the strain of raising the awl-carrier, the slot A⁹ is formed through the main part of the casing A and the outer end of the pin C⁷ is flattened to slide therein, as shown by Figs. 7 and 8.

The throat of the machine E has attached to or formed upon it the dovetail slide E', which is fitted to the groove A⁴ of the casing A, and this throat is secured in position by the bolt A⁵, which passes through the hole E².

The guideway for the peg-wood, as shown by Figs. 3, 11, and 16, is placed so that the line of travel of the peg-wood through it toward the driver is at right angles thereto. From the inner end of this peg-wood the pegs are sheared and then moved by the swinging shear F into the throat. The shear F is secured to the swinging arm F', which arm is hung upon the head of the bolt A⁵ by the pin F², and the arm F' is connected to the awl-carrier C by the link F³ and proper pin connections, as shown by Figs. 1, 2, 4, 5, and 6. As the awl-carrier moves down a peg is cut from the strip and moved into position to be driven, and when the awl-carrier moves up the peg-shear is swung back, so that another length of peg-wood can be moved forward by the feed-pawl E⁴, to be in turn cut off. The swinging part of the shear cuts against the stationary shear F⁴, secured in the bottom of the guideway for the peg-wood, as shown by Fig. 7. To hold the swinging shear up to its work and also to form a path for the peg to swing in while moving into position to be driven, there is secured to the throat the L-shaped piece E³, Figs. 1, 2, 4, 5, 6, and 10. The peg-wood is fed up to the shears by the scratch feed-pawl E⁴, Figs. 10, 11, 12, and 13, which is pressed forward by the spring E⁵ to feed the peg-wood and pressed back to take a fresh hold thereon by the wedge or cam B⁶, which at the proper time passes down through the hole E¹⁰, formed in the throat for that purpose and so positioned that the cam B⁶ just clears the top of the peg-wood. The cam B⁶ is made of such length that it will not move back the feed-pawl E⁴ until the preceding peg has been driven sufficiently far into the work to be withdrawn from the nozzle G when it is moved from the place where the machine was operated.

The peg-wood feed-pawl E is hung under the guideway upon the pin E⁶ and is provided with the slot E⁷, which allows it to have the

requisite motions, and the spring E⁵ acts upon the pawl in such a manner that it serves to press the points of the pawl up into the peg-wood as well as to move it forward. The 5 retainer-pawl E⁸ is hung upon the pin E⁶ so that its point is in contact with the peg-wood about the width of one peg back of the place where the points of the feed-pawl E⁴ will engage with said peg-wood, and the spring E⁹ 10 presses the point of this retainer-pawl up into the peg-wood and prevents backward motion thereof when the cam B⁶ is operating.

After the peg has been sheared and moved under the driver it is held in position by two 15 adjoining sides of the throat, the face of the shear, and one side of the awl, with the end of the driver just in contact with its head, as shown by Fig. 14. When the continued descent of the driver has moved the peg a short 20 distance down, the awl commences to move up and the peg is carried into the nozzle of the machine, where it is guided by the two opposite sides of the nozzle G, on one side by the awl and on the other side by the register- 25 point G', hung upon the pin G², Figs. 14 and 15. A spring G³, secured to the under part of the throat E by the screw G⁴, holds the register-point up to the side of the awl, until the peg, pressing between the awl and register- 30 point, moves said peg over to reach the hole made by the awl. When the point of the peg has reached the stock into which it is to be driven, the awl is nearly withdrawn from the stock and the register-point has moved the 35 end of the nozzle G over the hole just made by the awl and into which the peg is then driven, as shown by Fig. 15. This arrangement of parts of the peg-delivery mechanism causes the peg to be fairly driven no matter 40 at what inclination the operator may hold the peg-driving machine.

Having thus described our invention, its construction and mode of operation, we claim and desire to secure by Letters Patent of the 45 United States—

1. In a hand peg-driving machine, the combination of casing carrying and guiding suitable awl and peg driving mechanism consisting of two parts connected by dovetails, a

swinging lever pivoted between said parts, 50 and a bolt holding said parts fixed in position, and upon which said lever is pivoted substantially as shown and described.

2. In a hand peg-driving machine, the combination of casing, carrying and guiding suitable awl and peg driving mechanism, a support for the peg guiding, feeding, and the stationary member of the peg-wood shear connected thereto by dovetails, a bolt to fix 55 said support in position, and the swinging member of the peg-wood shear pivoted to said bolt, substantially as shown and described.

3. The combination in a hand peg-driving machine of the driver-plunger B with the tooth B⁸, the awl-carrier C, the pawl C³ with 60 the extension C⁴, the spring C⁵ and the cam A⁷ on the casing A all operating substantially as shown and described for the purpose set forth.

4. The combination in a hand peg-driving 70 machine of the compound swinging lever D, D', and D² mounted upon the bolt A³, the driver-plunger B provided with the pin B⁷ and the awl-carrier C having the roll secured thereto, all operating substantially as shown 75 and described for the purpose set forth.

5. In a peg-driving machine the combination with suitable peg-feeding, and peg-driving mechanism having a horizontal peg-wood guideway set at an angle substantially as described to the awl and driver, of a swinging peg-wood shear and suitable operating mechanism which shears a peg from the angular-held peg-wood and swings the same under the driver by the contact of the square cutting 85 edge of said shear against said peg, substantially as shown and described.

6. In a peg-driving machine the combination with the delivery-nozzle, awl, and driver thereof, of the swinging register-point G' and 90 spring G³ all operating substantially as shown and described.
